Albert S. Margason
BY *John A. Fairsmith*
ATTORNEY

UNITED STATES PATENT OFFICE.

ALBERT S. MARGASON, OF SAN JOSE, CALIFORNIA.

WINDSHIELD FOR CLOSED MOTOR CARS.

Application filed August 18, 1923. Serial No. 658,154.

To all whom it may concern:

Be it known that I, ALBERT S. MARGASON, a citizen of the United States, and a resident of San Jose, in the county of Santa Clara and State of California, have invented certain new and useful Improvements in Windshields for Closed Motor Cars, of which the following is a specification.

In building closed motor cars it is customary to provide the doors with vertically sliding sashes whereby ventilation of the car may be effected. But these windows are so arranged that when the sashes are dropped and the car is in motion, strong currents of air enter therethrough and not only cause great physical discomfort to the occupants of the car but not infrequently cause the development of more or less severe colds.

It is the object of this invention to provide means for deflecting the air currents in such a manner as to prevent undesirable eddies and currents of air in the car when the window sashes are open and the car is in motion.

It is another object of the invention to provide a means of the character indicated that will not interfere with the vision of the occupants of the car.

It is still another object of the invention to provide a means of the character indicated that will be rigidly mounted upon the car door and consequently movable with the door and free from vibration independently of its support.

I attain these objects by means of the mechanism illustrated in the accompanying drawings, in which,—

Figure 1 is a side elevation of the device in position on a car door.

Figure 2 is a section on line 2—2 of Figure 1.

Figure 3 is a diagrammatical illustration showing the position of the device relative to the car body and the door window.

Referring more particularly to the drawing, I show at 1 the body of a closed car, 2 a door therein, 3 the window opening in said door, and 4 the vertically movable sash in said window opening.

In applying my invention to a car door window, I provide two brackets as 5—5. Each bracket comprises a triangular portion 6 having a flange 7 turned at right angles thereto along one edge of one leg of the triangle, and provided with orifices whereby

the same may be screwed to the door 2. That edge of the element which forms the hypotenuse of the triangle is turned at right angles to the normal plane of the element as shown at 8 and provided with a groove 9, the parts 7 and 8 extending in opposite directions.

A sheet of glass 10 is now set in the opposed grooves 9—9 of a pair of these brackets and secured therein in any suitable manner not shown. The two brackets and the glass shield being assembled it only remains to fasten it upon the frame of the car door as shown, that is with the brackets positioned in parallel relation to the top edge 70 of the door and adjacent to the top and bottom edges of the window opening therein, and with the glass shield fitting snugly against the door frame adjacent to and parallel with the forward vertical edge of the 75 window opening, the said glass then sloping outwardly and backwardly from the car body.

It is considered desirable to have the triangular parts 6—6 present an unbroken surface whereby air currents are prevented from sweeping around either the upper or the lower edge of the device and so into the car.

The diagrammatical illustration in Figure 85 3 will clearly illustrate the results secured by the use of my improved shield upon a closed car when the same is in motion. With the window of the door open the air would ordinarily enter therethrough with greater 90 or less force according to the speed of the car, these air currents eddying freely and with some force about the heads of the occupants of the car as indicated by arrows 11. The only alternative to such a condition has heretofore been to close the sash in the door. This is not usually desirable, of course, because the air in the tightly closed car soon becomes foul.

By applying the shield as described, however, the air currents are deflected sufficiently to pass by the open window and strike the car to the rear thereof. Since most closed car bodies taper somewhat toward the front the tendency of the air to enter an 105 open window is much greater than if the sides were parallel. It is desirable, therefore, to so proportion the shield that its outer vertical edge be substantially in alignment with the corresponding rear vertical 110

edge of the car body in a plane parallel to a plane bisecting the body longitudinally and vertically.

Results are obtained by this arrangement 5 that are even superior to results that might be obtained upon a car having parallel sides for the reason that the angular space 12 becomes a more or less "dead air" space, or a 10 space filled with minor eddies and consequently there is no excessive passage of air 15 into the car nor any excessive passage of air out of the car. No matter how great the speed of the car may be no undue circulation of air within the car is apparent to 20 occupants thereof.

This device is rigidly mounted upon a car door in such a manner as to become essentially an integral part thereof. The angular relation of the glass portion to the car 25 body is fixed, and the angle is such as in no way to interfere with the usual normal functioning of the door.

It might be further mentioned that the device in deflecting the air currents also 25 materially reduces the quantity of dust, in-

sects, etc., that ordinarily blows into a car when atmospheric conditions are such as to render the opening of the door sash imperative.

It is to be understood, of course, that while 30 I have herein shown and described one specific embodiment of my invention, changes in form, construction and method of application may be made within the scope of the appended claim. 35

I claim:

A shield for car windows comprising a pair of brackets, each bracket comprising a triangular portion having a flange turned at right angles thereto along the edge of 40 one leg of the triangle, and means for securing the same to a door, that edge of the element forming the hypotenuse of the triangle being turned at right angles to the normal plane of the element and provided 45 with a groove, and a transparent shield fixedly mounted in the opposing grooves of the two triangular elements.

ALBERT S. MARGASON.
